HEINRICH DREWELL, OF CHARLOTTENBURG, GERMANY.

LINOTYPE OR COMPOSING-MACHINE.

No. 868,535.

Specification of Letters Patent.

Patented Oct. 15, 1907.

Application filed April 18, 1907. Serial No. 369,100.

To all whom it may concern:

Be it known that I, HEINRICH DREWELL, a subject of the German Emperor, residing at Charlottenburg, near Berlin, Germany, have invented new and useful Improvements in Linotypes or Composing-Machines, of which the following is a specification.

The present invention relates to an improved linotype or composing machine.

When type is set up or composed by means of a register band which is made in a special perforating machine, this band is either sent into the machine immediately after it is produced, or it is first wound up on a spare drum. The manner in which the composing machine operates is somewhat different in the two cases. When making the band, the composer commences, of course, at the commencement of the text which is to be set up. If the band is sent directly into the machine, the latter must operate in the same sequence as the composer at the perforating machine. If, however, the band is first wound up, only the last end of the band is free to be inserted into the composing machine. If it is wished to avoid unwinding the band, the machine must in this case commence with the last letter of the matter which is to be produced and compose backwards.

If the automatic operation of the composing machine is to bring about an increase in speed, the machine must operate so quickly that it works off the bands, which are prepared simultaneously by several compositers, in a period of time which is comparatively short as compared with that required for producing them. Such being the case, winding the band up cannot be entertained. On the other hand there are certain disadvantages in the machine composing backwards. It is not possible to compose on it single lines, such as lines corrected in proof reading for example, directly without register bands, say from a separate keyboard. Further, for rather long compositions, the bands must first be completely finished before they can be put into the composing machine, which causes a loss of time which is inadmissible in the production of newspapers. Machines which work backwards have a further disadvantage which is common to those which work forwards, namely, a band which has once been used and wound up after use must first be unwound again and then wound up anew in case it is to be used a second time.

Now an important object of the present invention is to avoid the disadvantages which are attached to the two ways of employing register bands, and to unite their advantages. Accordingly the composing machine in accordance with the present invention is made in such a manner that it can assemble types or matrices and whole lines in lines in two opposite directions, in agreement with the direction in which the machine composes in any given case. In principle it is of no importance whether the types or matrices are assembled

in lines in both directions in the same assembling or collecting device, or whether two such devices are provided of which the one places the types or matrices in line in the one direction and the other in the opposite direction. The same holds good for the assembling device for the lines.

In order that the invention may be clearly understood reference is made to the accompanying drawing in which one embodiment is shown by way of example, 65 said embodiment being applied to a linotype machine which is operated automatically by means of register bands.

In the drawing:—Figure 1 is an elevation, partly in section, of part of the machine showing the double assembling device, as well as the reversing mechanism, 70 and Fig. 2 is a plan, partly in section, of the second matrix assembling device with the retaining hooks on an enlarged scale.

Similar reference numerals and letters denote 75 similar parts in both views.

Referring to the drawing, 1 is an assembling elevator, 2 an assembling block which receive together the matrices which fall from the supply conduits 5 and from the driving belt 6.

In the assembling elevator 1 the matrices are assembled in line in known manner from right to left; in the assembling block 2 they are placed in line from left to right. When the matrices are to be put into line in the assembling elevator, the latter is raised into the position shown by the dotted line 4. In this position of the elevator 1 the matrices which come from the magazine fall on to a plate 7 which has been pushed forwards from the position in which it is shown in the drawing; the matrices are then pushed into the assembling elevator 90 by a tongue 9 which is rocked by the rotating cam 8. The cam 8 is driven by a ratchet wheel 99 engaging with a wheel 98. The latter engages with a wheel 101 which is mounted on a shaft 102 driven in any well known manner. The matrices are assembled in the elevator against the upper part of a holder or cheek 10 which gradually recedes as the matrices are collected.

When assembling block 2 is used, in order to assemble the matrices in line in the opposite direction, the tongue 9 remains stationary, plate 7 is drawn back to 104 the left, and the matrices fall into the front part of block 2 in which they are assembled. To hold the tongue 9 stationary, the wheel 98 being mounted upon a sliding bar 97 the action of which is described further on, is withdrawn from the wheel 102. They are here 108 situated between the lower part of the cheek 10 and a holder or cheek 11. Cheek 10 is revolubly attached to the end of a bar 12 and is provided with a shoulder 13. Between the latter and a shoulder 14 of the bar 12 is situated a spring 15 which presses the upper end of the 11 check or lever 10 as far as possible to the right. In the position in which it is drawn in the figure, the upper

end of the lever 10 is lying against the extreme left-hand end of channels or conduits 5 which correspond to the guides or channels G of the linotype-machine described in the specification of Letters Patent 436532. 5 The bar 12 is reciprocated or vibrated by a special device, whereby the matrices are pushed one after another into the assembling block or collector 2. The cheek 11 is attached to a slide 16; the latter slides on the bar 12 and is under the action of a spring 17. The 10 latter engages on the one hand the pin 18 attached to the bar 12, and on the other hand the pin 19 fastened in the slide 16 and tends to move said slide 16 to the left opposing the action of this spring 17; the cheek 11 recedes in front of the matrices which are being assembled 15 or alined against it. Hooks or latches 20 and 21 are arranged in block 2 which seize and hold the matrices so that the latter cannot follow the lever 10 when it returns.

The reciprocating movement of the bar 12 is brought 20 about as follows:—A shaft 22 which carries a quadrilateral disk 23 is driven from the main shaft of the composing machine by means of a belt 127; the arm 24 of a bell-crank lever 24, 25 provided with a pulley 125 lies against said disk 23; a pawl 26 is pivoted to the 25 other arm 25 of the same lever. This pawl engages the teeth 27 of the bar 12 and moves the bar to the right against the action of the spring 15. The bar 12 is also allowed to slide back again in correspondence with the oscillations of the lever 24, 25. In consequence of the 30 pressure which the upper end of the lever 10 exercises against the end of the conduits 5, the bar 12 tends to move to the left.

After one line of matrices has been completely assembled, it must be brought in front of the casting 35 device. For this purpose it is conveyed in the first place from assembling block 2 into assembling block 1 and it is then conveyed further in known manner. The following means serve for conveying the line from block 2 into block 1:—A controlling plate 28 which can 40 be displaced somewhat longitudinally on two guide-screws 29 and 30 is arranged over the bar 12 to the right of block 2. A spring 31 which engages the screw 29 on the one hand and the pin 33 on the other hand tends to pull the plate 28 to the left from its inoperative 45 position as shown in the drawing. This is prevented by a nose 34 of the plate 28 which lies against a similar nose of a lever 35. The lever 35 is revoluble round the screw 39 and carries the armature 36 of an electromagnet 37. Instead of this electromagnet 37 50 any other suitable device for moving the lever 35 may be employed. A spring 38 tends to keep the armature 36 away from the electromagnet 37; if the latter is energized however, which occurs at the conclusion of each line, it attracts its armature and releases the lever 35, 55 the nose 34 and therefore the controlling plate 28, and the latter moves to the left and operates. The following movements occur:—The lifter 40 which is attached to the controlling plate 28 passes with its slanting face 41 under the pin 42 attached to the pawl 26 and raises 60 the latter out of the tooth 27 of the bar 12. Further, a pin 43 which is attached to the controlling plate 28 raises a dog 45 from the tooth 27, said pin 43 hitting the arm 44 which, together with the dog 45, forms a bell-crank lever which is revoluble round a 65 screw 126. The bar 12 is now free to move to the left

into its discharge position. In order to effect this movement a pin 47 on the controlling plate 28 presses against one arm of a bell-crank lever 48, 50, the arm 50 of which lifts the rack 52 by means of a pulley 51 against a rotating disk 54. The rack 52 is pivoted at 70 53 to the bar 12. The disk 54 which is provided with toothing or a rubber cover is mounted on the continuously rotating shaft 22. When the rack 52 is pressed against the disk 54, the bar 12 is pushed to the left into its discharge position. The latter thus carries with it 75 the line of matrices between the holders or cheeks 10 and 11. The latches or hooks 20 and 21 are made inoperative for this moment by the controlling plate 28. Namely, the beveled hooks 20 and 21 are fastened to rods 55 and 56 which are mounted on a plate 57. 80 When the controlling plate 28 is displaced to the left, a plate 58 lies against said plate 57, said plate 58 being attached to the plate 28. The rods 55, 56 with the hooks 20 and 21 are thereby pushed to the left and are disengaged from the bodies of the matrices because of 85 a special device. Fig. 2 shows this latter device more clearly. The two latches or hooks 20 as well as the two lower latches 21 are situated one in the front side and the other in the rear side of the assembling block 2. These hooks have beveled faces 60 which lie 90 against similar beveled faces 61 of the body 2 of the block. Now if the resilient hooks 20, 21 are moved to the left by the rods 55 and 56, they will be pressed out from the interior of the assembling block by the action of the beveled faces 60, thus releasing the line 95 120 of matrices. The plates 57 and 58 are connected by a pin 63 provided with a head 64, so that when the plate 28 has been moved quite back to the right again the hooks 20 and 21 are again drawn in. The pin 33 of the controlling plate 28 engages in the slot 67 of the 100 bell-crank lever 68, 70 and drives the latter when the plate 28 is moved to the left. The end of the arm 70 then comes under the nose of a catch or hook 71 which is controlled by the spring 72, and thus prevents both the bell-crank lever 68, 69 and 70 and the controlling 105 plate 28 from moving backwards, the controlling plate 28 remaining in its operative position.

At a suitable place on the underside of the bar 12 there is toothing 66. The dog 65 can engage in this toothing and hold the bar 12 in the extreme left-hand 110 or discharge position after the line of matrices has been pushed out of block 2 into block 1. In the assembling block 1 there are hooks or latches 121, 122 similar to the hooks 20 and 21 in block 2. The hooks 121 and 122 cannot be displaced however; they hold fast the line 115 which is set up in block 1. As soon as the entire line has been conveyed from block 2 into block 1, the latter is raised by known means to the height of the matrix guide 73 at 123, in order that the line may be conveyed further from there.

When the line is being transferred from one assembling block to the other, a nose 75 at the right-hand end of the bar 12 moves a bell-crank lever 76, 77, 78, to the arm 78 of which a spring 79 is attached. This spring 79 is also attached to the lever 80, and the latter is mounted 125 on the pivot of the bell-crank lever 68, 70, and engages by means of a slot with a pin 81 in said bell-crank lever. When the spring 79 is fully stretched, it tends to rotate the bell-crank lever 68, 70 against the tension of the spring 31 which is on the controlling plate 28. This 130

rotation is in the first place prevented by the hook 71. When the line arrives in assembling block 1, however, a nose 74 on the slide 16 seizes the hook 71 and pulls it off from the arm 70 of the bell-crank lever. The fully 5 stretched spring 79 now overcomes the spring 31 and drives back the bell-crank lever 68, 69, 70 and also the plate 28 into the commencing or inoperative position again.

The bar 12 remains in its extreme left-hand position 10 until the assembling block 1 is nearly as high as the guide 73. The assembling block here hits against a two-armed lever 82, the other arm 84 of which is positively connected by a rod 85 with a lever 86. The lever 86 is fastened on the pivot 87 carrying the pawl 65, said 15 pivot projecting through the side 3 of the frame. Now when the assembling block 1 hits under the lever 82, the dog 65 is thereby withdrawn from the toothed 66 of the bar 12, and the latter is drawn back to the right into its normal operative position by the spring 79 and 20 the bell-crank lever 76, 77, 78, until the upper end of the cheek 10 lies against the extreme end of the conduits 5. The strength of the almost entirely released spring 79 is not sufficient to completely return the bar 12 into its normal operative or commencing position. 25 Accordingly the following means for effecting this have been devised:—

The upper toothed 27 of the bar 12 extends so far that the pawl 26 engages it before the cheek 10 hits against the extreme end of the first conduit 5 and before 30 the spring 79 is completely relaxed. Besides the pawl 26 and earlier than this the dog or pawl 45 also engages the toothed 27. Now as soon as the bar 12 has been moved so far to the right that the pawls 26 and 45 simultaneously engage in the toothed 27, these operate like 35 a pawl and ratchet gear on account of the reciprocating motion of the pawl 26, and draw the bar a definite number of teeth to the right at each stroke. This continues until the pawl 45 falls into the gap 88 in the teeth; the switching or feeding action then ceases and the bar 12 40 follows the reciprocating motion of the pawl 26. The entire device is thus set for assembling a new line of matrices in assembling block 2.

The assembling of matrices in block 2 corresponds to composing the lines from the last letter of the alphabet of the matter to be set up, namely to composing backwards. If it is wished to change to the reverse mode of composing, namely to composing forwards, the manner in which the individual parts operate must be changed. To bring about this change reversing 50 mechanism is provided which is described hereafter.

Below the assembling block 1 is mounted a shaft 90 provided with a crank-handle 91 and two eccentrics 92 and 93. The block 1 rests on the eccentric 92. When the handle 91 is rotated 180°, the eccentric 92 55 raises the block 1 so high that its upper face is at the level of the dotted line 4. The matrices can now enter directly into this assembling block. The eccentric 93 is also rotated by the shaft 90. The fork 94 of the lever 95 embraces the latter eccentric, and is moved 60 correspondingly when said eccentric 93 is rotated. With the lever 95 there is connected firstly a bar 97 which carries a friction pulley or a toothed wheel 98 at its upper end; this wheel is in continuous engagement with a wheel 99 on the shaft 100 of the cam 8. When 65 the handle 91 is rotated 180° from the position shown,

the lever 95 is raised and with it the bar 97; the toothed wheel 98 thereby engages with a wheel 101 which is fastened on the shaft 102 of the pulley 103 which is driven by the belt 6. The shaft 102 and the wheel 101 rotate continuously. As soon as the wheels 98 and 101 70 come into engagement, the cam 8 is also driven from the shaft 102. The assembling plate 7 is also hereby simultaneously set in position. It is fastened to a slide 108 which is held displaceable on the frame plate 3 by means of two screws 106 and 107. On the rear of the 75 slide 108 is a pin 105 which projects through the frame plate into a slanting slot 104 of the bar 97. When the bar 97 is pushed from below upwards the slide 108, and with it the assembling plate 7, is displaced from the right to the left, whereby the plate 7 is set for assembling the matrices in front of the opening of the assembling block 1. 80

With the lever 95 there are also connected two arms 96 and 109 which rotate with it in common round the pivot 117. At one extreme position of reversal the 85 arm 109 lies against the pin 112 of the small lever 113, the latter being fastened on a pivot 114 which passes through the frame plate 3. The pivot 114 carries the lever 115 provided with the nose 116 in front of the framing 3; when reversal is effected in consequence of 90 the movement of the arm 109, said nose 116 lies in front of the nose 74 of the slide 16 and prevents the cheek 11 participating in the motion of cheek 10 to the left. In order that this movement of cheek 10 may be effected, a rod 110 which is also connected with the lever 95 pulls the left end of the lever 35 downwards and releases the nose 34 together with the controlling plate 28, leaving the latter free to move to the left. The pawls 26 and 45 are hereby raised from the toothed 27 of the bar 12. Now in order that the bell-crank lever 100 48, 49, 50 and the rack 52 do not operate, the pivot 49 of the bell-crank lever 48, 50 is fastened in the bar 111. This bar is pivoted to the arm 96 of the reversing lever 95 and follows its movements. When reversal from the position shown in the drawing is effected, the bar 111 105 is drawn downwards and it brings the arm 48 of the bell-crank lever out of reach of the pin 47. The arm 50 rests with its extreme end on a stop 118. Further, the spring 79 is also made inoperative. Namely the pivot 77 of the bell-crank lever 76, 77, 78 is journaled in the 110 extreme right-hand end of the lever 96 and is brought downwards when the lever is reversed. The arm 76 then leaves the nose 75 and lies against a fixed supporting face 119. Now as soon as the matrices go into the assembling block 1 the cheek 10 recedes against the 115 action of the spring 17, as the slide 16 is held fast by the lever 115. The tensions of the spring 15 and 17 are so proportioned that the cheek 10 is not placed slantwise in an unsuitable manner. The front side of the channels 5 for supplying the matrices is closed as far 120 as the assembling block 2 by a plate 124 which is shown in dotted lines.

The device above described in accordance with the present invention may also be used for type setting machines. In the first place the possibility of being 125 able to assemble the constituent parts of the lines, whether types or matrices, both from right to left and from left to right is an essential feature, and also the arrangement of a double assembling block for this purpose.

I do not claim broadly the combination, in an auto- 130

matic composing machine, of an assembling block with means for assembling matrices in a line in said block; but

I claim.

- 5 1. In combination, in an automatic composing machine, an assembling block, means for assembling matrices in a line in said block, another assembling block, means for assembling matrices in a line in the latter assembling block, and means for transferring the line of matrices 80
10 from the latter assembling block into the former assembling block as set forth. 85
- 15 2. In combination, in an automatic composing machine, an assembling block, means for assembling matrices in a line in one direction in said block, another assembling block, means for assembling matrices in a line in the opposite direction in the latter assembling block, and means for transferring the line of matrices from the latter assembling block into the former assembling block as set forth. 90
- 20 3. In combination, in an automatic composing machine, an assembling block, mechanism for alining matrices in said block, a source of power, another assembling block, mechanism driven from said source of power for alining matrices in the latter block, mechanism driven from said 95
25 source of power for transferring a line of matrices from the latter block into the former block, and reversing means for connecting the former alining mechanism with the source of power and simultaneously disconnecting the latter alining and transferring mechanisms from said 100 source of power as set forth. 105
- 30 4. In combination, in an automatic composing machine, an assembling block, mechanism for alining matrices in said block, a source of power, another assembling block, mechanism driven from said source of power for alining 110
35 matrices in the latter block, mechanism driven from said source of power for transferring a line of matrices from the latter block into the former block, and reversing means for connecting said alining mechanisms alternately with said source of power, as set forth. 115
- 40 5. In combination, in an automatic composing machine, an assembling block, mechanism for alining matrices in said block, a source of power, another assembling block, mechanism driven from said source of power for alining 120
45 matrices in the latter block, mechanism driven from said source of power for transferring a line of matrices from the latter block into the former block, means adapted to connect said alining mechanisms with said source of power and reversing means for alternately preventing said alining mechanisms being operated by said means connecting them 125
50 with the source of power as set forth. 130
- 55 6. In combination, in an automatic composing machine, an assembling block, detent means in the same, mechanism for assembling matrices in a line in said block, a source of power, driving means adapted to be driven from said 135
60 source of power for driving the latter mechanism, a second assembling block, a bar having detent means, a holder for matrices in said first block on said bar, a holder for matrices in said second block movable on said bar, reciprocating mechanism operated from said source of power adapted to engage said bar for alining matrices against said holder, a catch device in said second assembling block for said matrices against said holder, a controlling member for controlling the latter device and provided with driving members, means tending to operate said controlling 140
65 member, means for detaining said controlling member in its inoperative position, means for withdrawing the latter detaining means, whereby said controlling member operates, said bar is disengaged from said reciprocating mechanism and said catch device is released from said matrices by said driving member, conveying mechanism adapted to be operated by said controlling member and driven from said source of power for 145
70 driving said bar and transferring said second holder into the first assembling block, and reversing means for connecting said driving means for said first assembling-block mechanism with the source of power, for disconnecting said reciprocating mechanism from said bar and for preventing said conveying mechanism being set in operation by said controlling member as set forth. 150
- 75 9. In combination, in an automatic composing machine, an assembling block, detent means in the same, mechanism for assembling matrices in a line in said block, a source of power, driving means adapted to be driven from said source of power for driving the latter mechanism, a second assembling block, a bar having detent means and a pin, a holder for matrices in said first block on said bar, a spring-controlled slide, provided with a holder, movable on said pin on said bar for supporting matrices in said second block, reciprocating mechanism operated from said source of power adapted to engage said bar for alining matrices against said holder, a catch device in said second assembling block for said matrices against said holder, a controlling member for controlling the latter device and provided with driving members, means tending to operate said controlling member, means for detaining said controlling member in its inoperative position, means for withdrawing the latter detaining means, whereby said controlling member operates, said bar is disengaged from said reciprocating mechanism and said catch device is released from said matrices by said driving members, conveying mechanism adapted to be operated by said controlling 155
80 member as set forth.

ling member and driven from said source of power for driving said bar and transferring said second holder into the first assembling block, and reversing means for connecting said driving means for said first assembling-block mechanism with the source of power, for disconnecting said reciprocating mechanism from said bar and for preventing said conveying mechanism being set in operation by said controlling member as set forth.

10. In combination, in an automatic composing machine,
10 an assembling block, detent means in the same, mechanism
for assembling matrices in a line in said block, a source
of power, driving means adapted to be driven from said
source of power for driving the latter mechanism, a sec-
ond assembling block, a bar having detent means, a holder
15 for matrices in said first block on said bar, a holder for
matrices in said second block movable on said bar, recip-
rocating mechanism operated from said source of power
adapted to engage said bar for alining matrices against
said holder, a catch device in said second assembling block
20 for said matrices against said holder, a spring-pulled con-
trolling plate having a nose and provided with driving
members, means for engaging said nose and detaining
said controlling member in its inoperative position, means
for withdrawing the latter detaining means, whereby said
25 controlling member operates, said bar is disengaged from
said reciprocating mechanism and said catch device is
released from said matrices by said driving members,
conveying mechanism adapted to be operated by said con-
trolling member and driven from said source of power for
30 driving said bar and transferring said second holder into
the first assembling block, and reversing means for con-
necting said driving means for said first assembling-block
mechanism with the source of power, for disconnecting
said reciprocating mechanism from said bar and for pre-
35 venting said conveying mechanism being set in operation
by said controlling member as set forth.

11. In combination, in an automatic composing machine, an assembling block, detent means in the same, mechanism for assembling matrices in a line in said block, a source of power, driving means adapted to be driven from said source of power for driving the latter mechanism, a second assembling block, a bar having detent means, a holder for matrices in said first block on said bar, a holder for matrices in said second block movable on said bar, reciprocating mechanism operated from said source of power adapted to engage said bar for alining matrices against said holder, a catch device in said second assembling block for said matrices against said holder, a controlling member for controlling the latter device and provided with driving members, means tending to operate said controlling member, means for detaining said controlling member in its inoperative position, electrical means for withdrawing the latter detaining means, whereby said controlling member operates, said bar is disengaged from said reciprocating mechanism and said catch device is released from said matrices by said driving member, conveying mechanism adapted to be operated by said controlling member and driven from said source of power for driving said bar and transferring said second holder into the first assembling block, and reversing means for connecting said driving means for said first assembling-block mechanism with the source of power, for disconnecting said reciprocating mechanism from said bar and for preventing said conveying mechanism being set in operation by said controlling member as set forth.

12. In combination, in an automatic composing machine, an assembling block, detent means in the same, mechanism for assembling matrices in a line in said block, a source of power, driving means adapted to be driven from said source of power for driving the latter mechanism, a second assembling block, a bar having detent means, a holder for matrices in said first block on said bar, a holder for matrices in said second block movable on said bar, reciprocating mechanism operated from said source of power adapted to engage said bar for aligning matrices against said latter holder, a catch device in said second assembling block for said matrices against said holder, a spring-pulled controlling plate having a nose and provided with driving members, a lever pivoted to engage said nose, an electromagnet for disengaging said lever, whereby said

controlling member operates, said bar is disengaged from said reciprocating mechanism and said catch device is released from said matrices by said driving members, conveying mechanism adapted to be operated by said controlling member and driven from said source of power for driving said bar and transferring said second holder into the first assembling block, and reversing means for connecting said driving means for said first assembling-block mechanism with the source of power, for disconnecting said reciprocating mechanism from said bar and for preventing said conveying mechanism being set in operation by said controlling member as set forth. 85 90

13. In combination, in an automatic composing machine, an assembling block, detent means in the same, mechanism for assembling matrices in a line in said block, a source of power, driving means adapted to be driven from said source of power for driving the latter mechanism, a second assembling block, a bar having teeth, a holder for matrices in said second block movable on said bar, reciprocating mechanism comprising a shaft, carrying a quadrilateral disk, driven from said source of power, and a two-armed lever, carrying on one arm a wheel running on said disk, and a pawl pivoted to the other arm engaging said teeth, a catch device in said second assembling block for said matrices against said holder, a spring-pulled controlling plate having a nose and provided with driving members, a lever pivoted to engage said nose, an electromagnet for disengaging said lever, whereby said controlling member operates, said pawl is disengaged from said teeth and said catch device is released from said matrices by said driving members, conveying mechanism adapted to be operated by said controlling member and driven from said source of power for driving said bar and transferring said holder into the first assembling block, and reversing means for connecting said driving means for said first assembling-block mechanism with the source of power, for disconnecting said reciprocating mechanism from said bar and for preventing said conveying mechanism being set in operation by said controlling member as set forth. 110 115 95

14. In combination, in an automatic composing machine, an assembling block, detent means in the same, mechanism for assembling matrices in a line in said block, a source of power, driving means adapted to be driven from said source of power for driving the latter mechanism, a second assembling block, a bar having detent means, a holder for matrices in said first block on said bar, a holder for matrices in said second block movable on said bar, reciprocating mechanism operated from said source of power adapted to engage said bar for alining matrices against said latter holder, a catch device in said second assembling block for said matrices against said holder, a controlling member for controlling the latter device and provided with driving members, means tending to operate said controlling member, means for detaining said controlling member in its inoperative position, means for withdrawing the latter detaining means, whereby said controlling member operates, said bar is disengaged from said reciprocating mechanism and said catch device is released from said matrices by said driving member, a shaft, carrying a wheel, driven from said source of power, a member adapted to engage said wheel pivoted on said bar, a two-armed lever adapted to bring the latter member into engagement with said wheel with one arm, and adapted to be driven by said controlling member with the other arm, and reversing means for connecting said driving means for said first assembling-block mechanism with said source of power, for disconnecting said reciprocating mechanism from said bar and for preventing said two-armed lever being driven by said controlling member as set forth. 145 140 135 130 125 120

15. In combination, in an automatic composing machine, 150
an assembling block, detent means in the same, mech-
anism for assembling matrices in a line in said block, a
source of power, driving means adapted to be driven
from said source of power for driving the latter mech-
anism, a second assembling block, a bar having detent 155
means, a holder for matrices in said first block on said
bar, a holder for matrices in said second block movable on
said bar, reciprocating mechanism operated from said
source of power adapted to engage said bar for alining
matrices against said latter holder, a catch device in said 160

second assembling block for said matrices against said holder, a controlling member for controlling the latter device and provided with driving members, means tending to operate said controlling member, means for detaining 5 said controlling member in its inoperative position, means for withdrawing the latter detaining means, whereby said controlling member operates, said bar is disengaged from said reciprocating mechanism and said catch device is released from said matrices by said driving members, conveying mechanism adapted to be operated by said controlling member and driven from said source of power for driving said bar to its discharge position and transferring said second holder into the first assembling block, means adapted to be released by said bar for detaining said 10 controlling member in its inoperative position, means adapted to be released by said first assembling block when the same is raised for holding said bar in its discharge position, a reversing member, means connected with said reversing member and adapted to be operated by said bar for returning said controlling member to its inoperative position, whereby said reciprocating mechanism engages said bar and returns it to its normal operative position, means connected with said reversing member connecting said assembling mechanism for the first block with the 15 source of power, means adapted to be operated by said reversing member for preventing said latter holder entering said first assembling block when said assembling mechanism of said first assembling block operates, means connecting said reversing member with said means for detaining said controlling member in its inoperative position, and means for raising said first assembling block and reversing said reversing member, as set forth.

16. In combination, in an automatic composing machine, an assembling block, detent means in the same, mechanism for assembling matrices in a line in said block, a source of power, driving means adapted to be driven from said source of power for driving the latter mechanism, a second assembling block, a bar having detent means and a driving member, a holder for matrices in said first block 20 on said bar, a holder for matrices in said second block movable on said bar, reciprocating mechanism operated from said source of power adapted to engage said bar for alining matrices against said latter holder, a catch device in said second assembling block for said matrices against said holder, a spring-pulled controlling plate having a nose and provided with driving members, a lever engaging said spring, means for engaging said nose and detaining said controlling member in its inoperative position, means for withdrawing the latter detaining means, 25 whereby said controlling member operates, said bar is disengaged from said reciprocating mechanism and said catch device is released from said matrices by said driving members, conveying mechanism adapted to be operated by said controlling member and driven from said source of power for driving said bar to its discharge position and transferring said second holder into the first assembling block, means adapted to be released by said bar for detaining said controlling member in its inoperative position, means adapted to be released by said first assembling 30 block when the same is raised for holding said bar in its discharge position, a reversing member, a two-armed lever revoluble on said reversing member adapted to be operated by said driving member on said bar, a spring engaging said levers for returning said controlling member to its inoperative position, whereby said reciprocating mechanism engages said bar and returns it to its normal operative position, means connected with said reversing member connecting said assembling mechanism for the first block with the source of power, means adapted to be 35 operated by said reversing member for preventing said second holder entering said first assembling block when said assembling mechanism of said first assembling block operates, means connecting said reversing member with said means for detaining said controlling member in its inoperative position, and means for raising said first assembling block and reversing said reversing member, as set forth.

17. In combination, in an automatic composing machine, an assembling block, detent means in the same, mechanism for assembling matrices in a line in said block, a

source of power, driving means adapted to be driven from said source of power for driving the latter mechanism, a second assembling block, a bar having detent means, a holder for matrices in said first block on said bar, a holder for matrices in said second block movable on said bar, reciprocating mechanism operated from said source of power adapted to engage said bar for alining matrices against said latter holder, a catch device in said second assembling block for said matrices against said holder, a controlling member for controlling the latter device and provided with driving members, means tending to operate said controlling member, means for detaining said controlling member in its inoperative position, means for withdrawing the latter detaining means, whereby said controlling member operates, said bar is disengaged from said reciprocating mechanism and said catch device is released from said matrices by said driving members, conveying mechanism adapted to be operated by said controlling member and driven from said source of power for driving said bar to its discharge position and transferring said second holder into the first assembling block, means adapted to be released by said bar for detaining said controlling member in its inoperative position, means adapted to be released by said first assembling block when the same is raised for holding said bar in its discharge position, a reversing member, means connected with said reversing member and adapted to be operated by said bar for returning said controlling member to its inoperative position, whereby said reciprocating mechanism engages said bar and returns it to its normal operative position, a bar on said reversing member, a wheel on said latter bar, said wheel being adapted to connect said assembling mechanism for the first block with the source of power, means adapted to be operated by said reversing member for preventing said second holder entering said first assembling block when said assembling mechanism of said first assembling block operates, means connecting said reversing member with said means for detaining said controlling member in its inoperative position, and means for raising said first assembling block and reversing said reversing member, as set forth.

18. In combination, in an automatic composing machine, an assembling block, detent means in the same, mechanism for assembling matrices in a line in said block, a source of power, driving means adapted to be driven from said source of power for driving the latter mechanism, a second assembling block, a bar having detent means and a pin, a holder for matrices in said first block on said bar, a spring-controlled slide, having a nose, and provided with a holder, movable on said pin on said bar for supporting matrices in said second block, reciprocating mechanism operated from said source of power adapted to engage said bar for alining matrices against said latter holder, a catch device in said second assembling block for said matrices against said holder, a controlling member for controlling the latter device and provided with driving members, means tending to operate said controlling member, means for detaining said controlling member in its inoperative position, means for withdrawing the latter detaining means, whereby said controlling member operates, said bar is disengaged from said reciprocating mechanism and said catch device is released from said matrices by said driving members, conveying mechanism adapted to be operated by said controlling member and driven from said source of power for driving said bar to its discharge position and transferring said second holder into the first assembling block, means adapted to be released by said bar for detaining said controlling member in its inoperative position, means adapted to be released by said first assembling block when the same is raised for holding said bar in its discharge position, a reversing member, means connected with said reversing member and adapted to be operated by said bar for returning said controlling member to its inoperative position, whereby said reciprocating mechanism engages said bar and returns it to its normal operative position, means connected with said reversing member connecting said assembling mechanism for the first block with the source of power, an arm pivoted on said reversing member adapted to be placed in front of said nose on said slide when said reversing member is reversed, means connecting 140

said reversing member with said means for detaining said 'controlling member in its inoperative position, and means for raising said first assembling block and reversing said reversing member, as set forth.

- 3 said reversing member with said means for detaining said
4 controlling member in its inoperative position, and means
5 for raising said first assembling block and reversing said
6 reversing member, as set forth.

7 19. In combination, in an automatic composing machine,
8 an assembling block, detent means in the same, mechanism
9 for assembling matrices in a line in said block, a source of
10 power, driving means adapted to be driven from said
11 source of power for driving the latter mechanism, a second
12 assembling block, a bar having detent means, a holder for
13 matrices in said first block on said bar, a holder for mat-
14 rices in said second block movable on said bar, reciprocating
15 mechanism operated from said source of power adapted
16 to engage said bar for alining matrices against said latter
17 holder, a catch device in said second assembling block for
18 said matrices against said holder, a spring-pulled controlling
19 plate having a nose and provided with driving members,
20 a pivoted lever for engaging said nose and detaining
21 said controlling member in its inoperative position, means
22 for withdrawing the latter detaining means, whereby said
23 controlling member operates, said bar is disengaged from
24 said reciprocating mechanism and said catch device is re-
25 leased from said matrices by said driving members, conveying
26 mechanism adapted to be operated by said controlling
27 member and driven from said source of power for driving
28 said bar to its discharge position and transferring said sec-
29 ond holder into the first assembling block, means adapted
30 to be released by said bar for detaining said controlling
31 member in its inoperative position, means adapted to be
32 released by said first assembling block when the same is
33 raised for holding said bar in its discharge position, a re-
34 versing member, means connected with said reversing member
35 and adapted to be operated by said bar for returning
36 said controlling member to its inoperative position, where-
37 by said reciprocating mechanism engages said bar and re-
38 turns it to its normal operative position, means connected
39 with said reversing member connecting said assembling
40 mechanism for the first block with the source of power,
41 means adapted to be operated by said reversing member for
42 preventing said second holder entering said first assem-
43 bling block when said assembling mechanism of said first
44 assembling block operates, a rod attached to said reversing
45 member and to said lever for engaging said nose on said
46 controlling plate for detaining said plate in its inoperative
47 position, and means for raising said first assembling block
48 and reversing said reversing member, as set forth.

49 20. In combination, in an automatic composing machine,
50 an assembling block, detent means in the same, mechanism
51 for assembling matrices in a line in said block, a source of
52 power, driving means adapted to be driven from said
53 source of power for driving the latter mechanism, a second
54 assembling block, a bar having detent means, a holder for mat-
55 rices in said first block on said bar, a holder for mat-
56 rices in said second block movable on said bar, reciprocating
57 mechanism operated from said source of power adapted
58 to engage said bar for alining matrices against said latter
59 holder, a catch device in said second assembling block for
60 said matrices against said holder, a controlling member
61 for controlling the latter device and provided with driving
62 members, means tending to operate said controlling mem-
63 ber, means for detaining said controlling member in its in-
64 operative position, means for withdrawing the latter de-
65 taining means, whereby said controlling member operates,
66 said bar is disengaged from said reciprocating mechanism
67 and said catch device is released from said matrices by said
68 driving members, conveying mechanism adapted to be oper-
69 ated by said controlling member and driven from said
70 source of power for driving said bar to its discharge position
71 and transferring said second holder into the first assem-
72 bling block, means adapted to be released by said bar
73 for detaining said controlling member in its inoperative po-
74 sition, means adapted to be released by said first assem-
75 bling block when the same is raised for holding said bar in
76 its discharge position, a reversing member provided with a

77 fork, means connected with said reversing member and
78 adapted to be operated by said bar for returning said con-
79 trolling member to its inoperative position, whereby said
80 reciprocating mechanism engages said bar and returns it to
81 its normal operative position, means connected with said
82 reversing member connecting said assembling mechanism
83 for the first block with the source of power, means adapted
84 to be operated by said reversing member for preventing
85 said second holder entering said first assembling block
86 when said assembling mechanism of said first assembling
87 block operates, means connecting said reversing member
88 with said means for detaining said controlling member in
89 its inoperative position, a shaft, an eccentric on said shaft
90 embraced by said fork, another eccentric on said shaft car-
91 rying said first assembling block, and means for rotating
92 said shaft, as set forth.

93 21. In combination, in an automatic composing machine,
94 a bar (12) having teeth and provided with a shoulder
95 (14), a cheek (10) having a shoulder (13) pivoted on said
96 bar, a spring (15) between said shoulders, and reciprocating
97 mechanism detachably engaging said teeth, as set forth
98 for the purpose specified.

99 22. In combination, in an automatic composing machine,
100 a bar (12) having a pin and teeth and provided with a
101 shoulder (14), a cheek (10) having a shoulder (13) pivoted
102 on said bar, a spring (15) between said shoulders, a
103 slide (16) carrying a holder (11) and provided with a
104 groove movable on said pin on said bar, a spring engaging
105 said pin and said bar, and reciprocating mechanism de-
106 attachably engaging said teeth, as set forth for the purpose
107 specified.

108 23. In combination, in an automatic composing machine,
109 a frame (3), a shaft (102) mounted thereon, carrying a
110 pulley (101), a tongue (9) pivoted on said frame, a cam
111 (8) adapted to swing said tongue, a reversing member on
112 said frame and a wheel (97) connected with said revers-
113 ing member adapted to engage said pulley (101) and to
114 drive said cam (8) as set forth.

115 24. In combination, in an automatic composing machine,
116 a frame (3), a shaft (102) mounted thereon, carrying a
117 pulley (101), a tongue (9) pivoted on said frame, a cam
118 (8) adapted to swing said tongue, a support (108) for
119 matrices, having a pin (105), movable on said frame under
120 said cam and said tongue, a reversing member on said
121 frame, a bar, provided with a slanting slot adapted to en-
122 gage said pin (105), on said reversing member, and a
123 wheel (97) on said bar adapted to engage said pulley
124 (101) and to drive said cam (8), whereby when said wheel
125 (97) operates, said bar holds said support under said
126 tongue, as set forth.

127 25. In combination, in an automatic composing machine,
128 a frame (3), an assembling block (2) having slanting
129 faces within the same on said frame, rods (55, 56) ex-
130 tends into said block, beveled detents or latches (20, 21)
131 for normally engaging matrices on said rods, means for
132 pushing said rods and thereby said latches against said
133 slanting faces, whereby said latches are withdrawn from
134 their normal position and release the matrices as set
135 forth.

136 26. In combination, in an automatic composing machine,
137 a frame (3), an assembling block (2) having slanting
138 faces within the same on said frame, rods (55, 56) ex-
139 tends into said block, beveled detents or latches (20, 21)
140 for normally engaging matrices on said rods, a plate (57)
141 having a hole carrying said rods, a controlling member
142 (28), provided with a pin extending through said hole,
143 and means for reciprocating said member (28) whereby
144 said latches are operated as set forth.

145 In testimony whereof I have signed my name to this
146 specification in the presence of two subscribing witnesses.
